AKTIENGESELLSCHAFT, OF BERLIN-COPENICK, GERMANY

HIGH-SPEED BEETLING MILL

Application filed July 29, 1929, Serial No. 382,041, and in Germany August 28, 1928.

My invention relates to a high-speed beetling mill which is so designed that it operates in a manner as if it were a combination of a beetling mill with a whirling mill, the beetling members being suitably designed, as fully dealt with hereinafter.

I am aware of the existing beetling mills, as well as of the existing whirling mills. There are in these latter two shafts rotating 10 in opposite directions and operating members, for instance propellers or the like, apt to produce whirls or eddies. In contradistinction to these known whirling mills there is in my improved mill only one shaft, as in 15 a beetling mill, and the beetling members are so designed that they act like the propellers or the like of a whirling mill and produce brisk whirls or eddies which encounter one another in a manner fully described herein- 20 after.

The known beetling mills suffer from a rather severe drawback which consists in the air or other gas or gas mixture enclosed in the casing being driven against the inner 25 wall of the case by the centrifugal force arising during the rotations of the beetling members, in consequence whereof the air or gas rotates in the casing, that is to say, is kept in rotary motion by the rotating beetling 30 members, so that in front of each of these latter an air or gas cushion is formed by which the proper disintegration of the respective material is impaired.

The just mentioned drawback is dispensed 35 with in my present improved mill in which the otherwise rotating or circulating air or gas in the casing is subdivided into a plurality of individual currents which tend to circulate in opposite directions but continu- 40 ally intersecting one another and forming in this way whirls or eddies by which the particles of the material under treatment are pushed onto one another so as to mutually contribute to their disintegration.

45 The operation proceeds, thus, in this way that the material to be disintegrated is disintegrated first by direct impact with the revolving beetling members, and when this disintegrating process has proceeded so far 50 that the particles will float in the air, the

further disintegration to a still finer pulverulent or colloidal state proceeds in a twofold manner, in that the direct action of the beetling members is increased owing to the absence of the above-mentioned air cushions, 55 and in that the particles impinge upon one another, as already mentioned. The effect or result is an exceedingly fine reduction of the material to powder, even if this material is a metal; in fact, also steel having a strength 60 of from 80 to 90 kg. can be reduced to colloidal fineness, and this excellent effect is attained with a remarkable small expenditure of power. In other words: the efficiency of 65 this improved mill is very great.

This is the more the case as the number of operating members in this mill is smaller than formerly whereby also the weight of the operating members, or the weight of the complete mill, is reduced. This is highly impor- 70 tant especially in high-speed mills in that the bearings for the shaft supporting the operating members are preserved, and the life of the mill is prolonged. To judge correctly as regards these points it must be 75 borne in mind that it is hardly possible, if possible at all, to balance the revolving, i. e. operating members of mills of the types mentioned.

Another advantage from which, besides, a 80 prolongation of the life of the mill results is this that the shaft bearing the operating members within the casing can be supported at both its ends which is due to the fact that said members all revolve in the same 85 direction.

The invention is illustrated diagrammatically and by way of example on the accompanying drawing on which

Fig. 1 is an axial section through a mill 90 designed according to this invention, the means for supporting the casing and for driving the shaft having been omitted, and

Fig. 2 a side-view of one of the operating 95 members.

On the drawing, 1 denotes the mill casing which is completely closed, and is provided with two projections 2 and 3, one for the introduction of the material to be treated, as well as for the introduction of the convey- 100

ing air or other gas or gas mixture, and the other for the discharge of the product which is carried away from the casing by said air, etc. 4 is the shaft to which are attached, in the example shown, two operating members 5 and 6 constituting each two arms extending in opposite directions. These members are so keyed to the shaft as to extend parallel to one another.

10 The arms operate as beetling arms, and each of them is serrated on its beetling face in the manner shown, in that there are provided projections, resembling ratchet teeth and comprising oblique faces 8 (lefthand beetling member in Fig. 1) and 10 (righthand beetling member in Fig. 1), which are separated from one another by narrow shoulders 9 extending obliquely with respect to the shaft 4. The obliquity of the 15 faces of the two beetling members is counter to one another, as appears distinctly from Fig. 1. The broken lines in this figure and the arrows indicate the direction in which the particles encountered by the shoulders 9 are propelled further onward by them, the 20 respective directions being determined also by the shape of the interior of the casing at or near the bearings of the shaft, also as distinctly appearing from Fig. 1. The obliquity 25 of the faces 8 and 10 being very moderate, these faces are able to exert powerful blows upon the particles they encounter as they are rapidly revolving. The particles cannot, however, slide along the beetling arms to 30 35 ward the free ends thereof, being always intercepted by the next oblique shoulder 9 and thereby being propelled laterally, as indicated by the above-mentioned broken lines and the arrows. Because of this manner of 40 operation, the acceleration work uselessly spent in beetling mills of the old types is nearly completely utilized. The particles encountered by the beetling arms and receiving 45 their blows are continually propelled away from these arms nearly instantly after the blow, on the shortest way imaginable, and they cannot possibly exert, therefore, the detrimental cushioning effect decreasing the efficiency of the mill.

50 Besides, not only the particles of the material are propelled laterally by the shoulders 9, but the amounts of air or gas just encountered by them are also propelled away which greatly increases the efficiency of the mill.

55 In steam-turbine construction it is known to attain a great effect with blades of very small dimensions; just so it is possible to attain a remarkably high efficiency in beetling mills of the present improved design with a suitable plurality of narrow shoulders at the projections of the beetling arms.

60 I wish it to be understood that the particles of the material under treatment, as well as the air or gas, or gas mixture, do not move

inside the casing exactly in the directions as indicated by the broken lines and the arrows, but this is merely a component of the actual direction in that all said particles are subjected also to the blows of the arms exerted by their faces 8 and 10. The result of the two actions are whirls or eddies which proceed more or less obliquely and intersect one another whereby the particles of the material are very intensely agitated and their reduction to a very fine powder is very effectively promoted. This is due also to the fact that just by reason of the whirls or eddies continually intersecting one another the particles are again and again conducted into the path of the beetling members, or their blow faces respectively, so as to be again and again acted on by them.

65 I wish it further to be understood that I do not limit myself to the construction shown in the drawing merely by way of illustration. For instance, the beetling members 5 and 6 may be disposed at right angles with respect to one another, their number may be increased, they may be arranged nearer with respect to one another, or in groups, and so on. But, the arrangement shown in the drawing has proved highly effective and satisfactory, especially if the casing is shaped as shown in Fig. 1, i. e. bulged out at its 70 frontal walls, and the spaces between the beetling members and the casing wall, as well as between themselves, are practically equal.

75 I claim:

1. In a high-speed beetling mill, the combination with a closed casing, of a single rotatable shaft journalled in said casing, beetling members carried by said shaft and provided on their operating faces with obliquely disposed projections adapted to laterally propel the particles impinged upon, the projections of one of said beetling members being inclined opposite to those on the adjacent beetling member so as to produce intersecting eddying currents, said casing having enlargements to provide a free space for said currents.

100 110 115 120 125 2. In a high-speed beetling mill, the combination with a closed casing, beetling members carried by said shaft, each formed with oppositely extending arms, provided on their operating faces with obliquely disposed projections adapted to laterally propel the particles impinged upon, the projections on one of said beetling members being inclined opposite to those of the adjacent beetling member so as to produce intersecting eddying currents, said casing having enlargements to provide a free space for said currents.

130 3. In a high-speed beetling mill, the combination with a closed casing, of a single rotatable shaft journalled in said casing, beetling members carried by said shaft, each formed with oppositely extending arms pro-

vided on their operating faces with obliquely disposed teeth-like projections, the obliquity of the projections of one of the beetling members being opposite to the obliquity of the projections of the adjacent beetling member so as to produce intersecting eddying currents, said casing having enlargements to provide a free space for said currents.

4. In a high-speed beetling mill, the combination with a closed casing, of a single rotatable shaft journaled in said casing, beetling members carried by said shaft provided on their operating faces with obliquely disposed projections adapted to laterally propel the particles impinged upon, the projections of one of said beetling members being inclined opposite to those of the adjacent member so as to produce intersecting eddying currents, the frontal walls of said 20 casing being enlarged to provide a free space for said currents.

5. In a high-speed beetling mill, the combination with a closed casing, of a single rotatable shaft journaled in said casing, beetling members carried by said shaft, each formed with oppositely extending arms provided on their operating faces with obliquely disposed teeth-like projections, the obliquity of the projections of one of said 25 beetling members being opposite to the obliquity of the projections of the adjacent beetling member so as to produce intersecting eddying currents, the frontal walls of said casing being enlarged so as to provide a 30 free space for said currents.

35 In testimony whereof I affix my signature.
ERWIN KRAMER.
